UNITED STATES PATENT OFFICE.

MARCUS B. BEHRMAN, OF BROOKLYN, NEW YORK, ASSIGNOR TO THE LOX SEAL CORPORATION, OF BROOKLYN, NEW YORK, A CORPORATION OF NEW YORK.

PIN TICKET.

Application filed April 3, 1925, Serial No. 20,442. Renewed September 28, 1927.

This invention relates generally to marking tickets adapted to be attached to fabrics and articles of merchandise of various characters such as cloaks, dresses, hats and piece 5 goods to carry various information with reference thereto.

It is frequently the practice of individuals to order merchandise or garments sent home on approval and after wearing or otherwise 10 using the garment for a purpose other than that for which it was sent, to return the same to the store for credit or exchange.

Attempts have hitherto been made to prevent this practice by so associating or 15 pinning the marking ticket to the fabric or garment that it cannot be detached therefrom without detection and one character of device that has been developed for this purpose provides an arrangement whereby 20 the pin ticket consists of two folds of substantially equal length with one fold secured by a pin directly to the fabric or garment, and the other fold secured to the second fold so as to prevent the pin being reached and 25 manipulated without detection.

This arrangement necessitates the use of substantially double the amount of material than is actually required for the pin ticket markings themselves, and, in addition, in 30 such arrangements, the pin is positioned longitudinally of the pin ticket with the obvious inconveniences that arise therefrom when it is desired to handle the cloth or when it is desired to make notations on the 35 pin ticket.

Where I have attempted to overcome the objection incident to the use of the extra amount of material as in my Patent No. 1,492,552, granted May 6, 1924, by using a 40 shorter upper flap which covers only the pin head, I have found that this arrangement does not avoid the objection incident to the positioning of the pin longitudinally of the pin ticket, and in addition, exposes a portion 45 of the pin to view with the possibility that as a result of this the pin may be reached and manipulated.

One of the objects of my invention, therefore, is the provision of an arrangement 50 whereby on the one hand, I position the pin which secures the pin ticket to the fabric or other article of merchandise, transversely of the ticket and on the other hand, employ

a fold for a pin ticket which is just of sufficient size to cover this pin when so positioned. 55

Another object of my invention is the provision of a new, simple and inexpensive manner of attaching the pin ticket to a fabric or garment so that the ticket cannot be 60 removed without detection.

For the attainment of these objects and such other objects as may hereinafter appear or be pointed out, I have illustrated one embodiment of my invention in the 65 drawings wherein:

Fig. 1 is a front elevation of the ticket with both folds in the same plane;

Fig. 2 is a like view of the ticket secured to a fabric or garment, and prior to the 70 folding down of the upper flap; and

Fig. 3 is a top elevational view of the tag fully secured to the garment with the pin enclosed therewithin shown in dotted lines. 75

The pin ticket is preferably formed of any preferred or desired character of material such as relatively heavy paper stock or linen and may be given any preferred or desired dimensions and shape. 80

It comprises generally the pin ticket proper 11 and the flap 12 which are jointed along the line 13 which may be preliminarily scored or otherwise weakened or marked for convenience in folding. 85

It will be observed that upon viewing Fig. 1 of the drawing, that the upper part 14 of the pin ticket proper 11 which corresponds in dimensions with those of the flap 12 is a blank for reasons that will be understood. The various information which it is desired to place upon this pin ticket appears preferably below this space as indicated at 15 in the drawings. The flap or fold 12 is gummed on its upper surface as shown at 19. 95

In the use of this type of pin ticket, a pin 16 is inserted transversely of the space 14 as shown in Fig. 2 of the drawing, and for this purpose, perforations may be provided, if desired, and the gummed upper surface 19 of 100 the fold 12, then moistened or otherwise softened and the flap 12 then folded down on top of the pin ticket proper 11 thus sealing the pin on all sides and preventing manipulation of the pin without detection. 105 Upon viewing Fig. 2 it will be observed that

the pin 16 is inserted so that both the point 17 and the head 18 thereof are both positioned above the part 11 of the ticket.

While in the drawings, I have illustrated 5 and in the specification I have described my invention as having the gum applied to the flap 12 of the ticket, and the pin 16 as passed through the part 14 of the ticket proper 11, it will be understood that the part 14 of 10 the fold 11 could equally well have the gum applied thereto and that the pin could be passed through and secured to the fold 12.

It will be understood that the length of 15 the pin is less than the width of that portion of the pin ticket to which the pin is to be attached and that the size of the flap 12 shall be such that when folded, it completely covers the pin. It will also be understood that the flap 12 is gummed or otherwise secured to the part 14 of the ticket 11 along lines so as to completely enclose the 20 pin and in the embodiment of the invention, I have shown the flap 12 as having the gum applied to its whole surface so that the flap 12 will be secured to the part 14 all about and immediately adjacent to the pin regardless of the line along which the pin 25 is secured to the part 14.

Having thus described my invention and 30 illustrated its use, what I claim as new and desire to secure by Letters Patent, is

1. In a device of the character described, in combination, a substantially flat pin ticket having a pin carrying portion adapted to be 35 attached to the fabric, a flap of less length than the pin carrying portion and adapted to be folded over and over an adjacent part of the pin carrying portion, a pin to be passed through the pin carrying portion trans- 40 versely thereof for securing the ticket to a

fabric and of less length than the width of such pin carrying portion, said pin being so positioned on the pin carrying portion, with reference to the dimensions and position of the flap, that when the flap is folded 45 down on said pin carrying portion, it will completely cover the pin and extend therebeyond in all directions and adhesive means for securing said flap to the pin carrying portion only so as completely to enclose and 50 seal in the pin and prevent it being reached without disruption of the parts of the ticket.

2. In a device of the character described, in combination, a substantially flat pin ticket comprising a pin ticket proper and a flap, 55 the pin ticket proper consisting of an indicia bearing portion and a blank pin carrying portion adapted to be attached to a fabric, the flap being of less length than the pin carrying portion and adapted to be 60 folded over and cover an adjacent part of the pin carrying portion, a pin to be passed through the pin carrying portion transversely thereof for securing the ticket to a fabric and of less length than the width of 65 such pin carrying portion, said pin being so positioned on the pin carrying portion, with reference to the dimensions and position of the flap, that when the flap is folded down on said pin carrying portion, it will completely cover the pin and extend therebeyond in all directions and means for securing 70 said flap to the pin carrying portion only so as to completely enclose the pin by said ticket and prevent it being reached without disruption of the parts of the ticket.

In witness whereof, I have signed and sealed this specification, this 27 day of March, 1925.

MARCUS B. BEHRMAN.
